H. L. MILSTEAD,
CUT-OUT FOR AUTOMOBILES,
APPLICATION FILED SEPT. 4, 1920.

Patented Apr. 4, 1922.

By Watson E. Coleman

Attorney

UNITED STATES PATENT OFFICE.

HERBERT LEO MILSTEAD, OF CHANDLERVILLE, ILLINOIS.

CUT-OUT FOR AUTOMOBILES.

1,411,364.

Specification of Letters Patent. Patented Apr. 4, 1922.

Application filed September 4, 1920. Serial No. 408,167.

To all whom it may concern:

Be it known that I, HERBERT L. MILSTEAD, a citizen of the United States, residing at Chandlerville, in the county of Cass and 5 State of Illinois, have invented certain new and useful Improvements in Cut-Outs for Automobiles, of which the following is a specification, reference being had to the accompanying drawings.

10 This invention relates to cutouts for automobiles.

An important object of the invention is to provide in combination with a cutout, an operating mechanism therefor which is free 15 from the use of springs, thereby avoiding the necessity in either the opening or closing action of the cutout of exerting sufficient pressure to overcome such spring.

A further object of the invention is to 20 provide in a device of the above character a link connection between the cutout and the operating handle therefor the connection of the links being such that the cutout is effectually locked in the closed position when 25 moved to such closed position.

Other objects and advantages of the invention will become apparent throughout the following description.

In the accompanying drawings, wherein 30 for the purpose of illustration, is shown a preferred embodiment of my invention, and wherein like reference characters designate like parts throughout:

Figure 1 is a side elevation of a cutout 35 control constructed in accordance with my invention.

Figure 2 is a transverse sectional view partly in elevation, showing the mounting of the rock shaft, and

40 Figure 3 is a plan view showing the mounting of the cutout valve and its associated mechanism.

Referring now more particularly to the drawings, F designates the floor boards of 45 an automobile having arranged therebelow an exhaust pipe E. The exhaust pipe E is provided in the side wall thereof with a cutout portion forming an opening O. A valve V coacts with this opening to close the same and embodies outstanding pivot arms 10 and 11.

The yoke 12 is provided, composed of separable sections bolted about the exhaust pipe E as at 13, each of the sections of the yoke 55 embodying an outstanding ear 14 provided

with an opening for the reception of a pivot pin 10 or 11. The pivot pin 10 has secured thereto an arm 15.

Mounted in a bearing 16 secured to the under surface of the floor boards F is a rock 60 shaft 17 embodying downwardly extending arms 18 and 19. The arm 18 is provided at its lower end with a curved portion 20 terminating in a portion 21 substantially paralleling the arm 18. A link 22 has its upper 65 end pivotally connected with the end of the portion 21 as at 23, and its lower end pivotally connected as at 24 to the free end of the arm 15.

A lever 25 extends through a slot S 70 formed in the floor boards F pivotally mounted intermediate its ends in a bearing 26 secured to such floor boards. The lower end of this lever is connected by link 27 with the free end of the arm 19 carried by 75 the shaft 17.

It will be seen that when the upper end of the handle 25 is moved forwardly the arm 18 is moved rearwardly and the valve V shifted opening the cutout. When the 80 lever is moved in the opposite direction the valve is closed reaching such closed position at a time when the longitudinal axis of the link 22 lies radially in a line with the pivot point of the shaft 17. It will be obvious that 85 when in this position any movement imparted to the levers by the valve V because of pressure within the exhaust pipe E is impossible because of the fact that such force is not directed at an angle to the pivot 90 point of the arm 18 and consequently such force will merely tend to cause a binding of the shaft 17 in its bearing. Initial movement of the handle 25 forwardly breaks this straight line connection and the pressure 95 within the exhaust pipe assists in the opening of the valve V. If desired the link 22 may be made adjustable as indicated at 28 to compensate for any wear occurring at the pivot points 23 and 24 and in the bearing 16. 100

It will be obvious that my device by reason of its simplicity of construction and efficiency in operation is particularly well adapted for use, and it will likewise be obvious that some change may be made in the 105 same without departing from the spirit of my invention. I do not therefore limit myself to the construction hereinbefore set forth, except as so limited by the subjoined claims.

Having now described my invention what I claim is:

1. In valve operating mechanisms, means for shifting said valve to open and closed positions comprising, an operating lever and a connection, said lever and said connection embodying a member mounted to swing about a given axis, and a link connected with the member to be shifted longitudinally thereby, the longitudinal axis of said link aligning radially with the axis of said member when said valve is in the closed position.
2. In valve operating mechanism, means for shifting said valve to open and closed positions comprising an operating lever and a connection said lever and said connection embodying, a member mounted to swing about a given axis and an adjustable link connected with the member to be shifted longitudinally thereby, the longitudinal axis of said link aligning radially with the axis of said member when said valve is in the closed position.
3. In valve operating mechanism, means for shifting said valve to open and closed positions comprising an arm secured to said valve, a lever pivoted intermediate its ends,

a pivotally mounted rock shaft embodying a pair of arms, a link connecting one of the arms of said rock shaft and the arm of said valve, said link aligning radially with the pivotal mounting of the rock shaft when said valve is closed, and a link connecting the free end of the other of the arms of said rock shaft and one end of said lever.

4. In valve operating mechanism, means for shifting said valve to open and close the same comprising, an arm secured to said valve, a lever pivoted intermediate its ends, a pivotally mounted rock shaft, a pair of arms secured to said rock shaft, one of said arms being provided at its free end with a curved portion terminating in a portion substantially paralleling the arm, a link connecting the free end of the last named portion and the arm of said valve and aligning radially with the pivotal mounting of said rock shaft when the valve is in the closed position, and a link connecting the free end of the other of said arms and one end of said lever.

In testimony whereof I hereunto affix my signature.

HERBERT LEO MILSTEAD.
